UNITED STATES PATENT OFFICE.

JAMES D. ELSOM, OF CHICAGO, ILLINOIS, ASSIGNOR TO RAILWAY IMPROVEMENT COMPANY, OF NEW YORK, N. Y., A CORPORATION OF NEW YORK.

REGISTERING MECHANISM.

1,275,234.

Specification of Letters Patent. Patented Aug. 13, 1918.

Application filed March 1, 1912, Serial No. 680,807. Renewed June 7, 1916. Serial No. 102,351.

To all whom it may concern:

Be it known that I, JAMES D. ELSOM, a citizen of the United States, residing at Chicago, in the county of Cook and State of Illinois, have invented a new and useful Improvement in Registering Mechanism, of which the following is a specification.

My invention relates, more particularly, to registering mechanism for use in connection with electrically-propelled vehicles for registering the number of stops made by the vehicle, the length of the stops, and the number of passengers boarding and alighting from the vehicles during any given period of time, the record of the number and length of stops made by the vehicle being of value in determining the speed at which the vehicles should be run during different periods of the day for operating the vehicles with the maximum economy, and the record of the number of passengers boarding and alighting from the vehicles being of value in determining the number of vehicles required to be run during different periods of the day to accommodate the patrons of the road to the greatest possible practical extent.

Referring to the accompanying drawings, in which I have illustrated my invention as embodied in a register intended for use on an electrically-propelled car for registering the number and duration of stops and the number of passengers boarding and alighting from the car.

Figure 1 is a view in vertical sectional elevation of the register, the section being taken at the line 1 on Fig. 2 and viewed in the direction of the arrow. Fig. 2 is a view in elevation, partly sectional, taken at the line 2 on Fig. 1 and viewed in the direction of the arrow. Fig. 3 is a section taken at the line 3 on Fig. 2 and viewed in the direction of the arrow. Fig. 4 is a broken section taken at the line 4 on Fig. 1 and viewed in the direction of the arrow. Fig. 5 is a longitudinal sectional view of one of the indicating devices illustrated in Fig. 4; and Fig. 6, a diagrammatic view of the circuit connections for operating the register illustrated in connection with a trolley car.

Referring to the construction illustrated in Figs. 1 to 5 inclusive, the casing of the register is represented at 10 and, in practice, would be secured on the vehicle in connection with which it is to be used in any de-

sirable location. Journaled in bearings 11 and 12 located in the upper and lower ends of the casing 10 are shafts 13 and 14 carrying reels 15 and 16, respectively, the uppermost reel having wound thereon paper in strip form as represented at 17, the free end of the strip being connected with the lower reel 16. The strip 17 upon which the records, hereinafter referred to, are to be made, and which, in the operation of the register, is unwound from the upper reel 15 and wound upon the lower reel 16 by rotating the reel 16 in any desirable manner, as is well known in the art, passes over idlers 18 and 19 supported on shafts 20 and 21, respectively, journaled in the casing 10, and in its movement passes closely adjacent to a vertically-disposed plate 22 paralleling the strip 17 and secured to the sides of the casing 10, as indicated at 23, this plate containing an opening 24 for a purpose herein-after set forth. Located at the other side of the strip 17 is an hour impression wheel 25 and a minute impression wheel 26, the wheel 25 being fixed on a shaft 27 journaled in bearings 28 on the sides of the casing, and the wheel 26 being secured to a sleeve 29 surrounding and journaled on the shaft 27, whereby the wheels 25 and 26 may be rotated independently of each other. The numbers on the wheels 25 and 26 are spaced equi-distantly apart as represented, and extend beyond the periphery of the wheels, as is common in recording devices wherein provision is made for impressing upon a sheet 90 the hour and minute when such impression is made, these wheels opposing the opening 24 in the plate 22.

It will be understood from the foregoing that the wheel 25 is to be intermittently rotated a one-twelfth of a revolution every hour to bring the numerals representing the hours into successive registration with the opening 24, and that the wheel 26 be given a complete rotation once every hour to successively carry the numerals thereon representing the minutes into registration with the opening 24 in the plate 22 and into alignment with the hour numeral registering with the latter. As mechanism for operating wheels like the wheels 25 and 26 is commonly employed in certain types of indicators, it is not deemed necessary that detailed mechanism for thus operating the wheels 25 and 26 be illustrated or described.

In the drawings, the shaft 27 and sleeve 29 are shown as provided with pulleys 30 and 31, respectively, these pulleys, in practice, being connected as through the medium of belts 32 and 33 with clock-mechanism of any suitable construction, the casing of which is represented at 34, in a manner to cause the shaft 27 and wheel 25 to be rotated once every hour intermittently as stated, and the sleeve 29 and wheel 26 to be rotated throughout a complete revolution once every hour. Located between the wheels 25 and 26 and the plate 22 is a plate 35 secured at its ends to the casing as indicated at 36 and containing an opening 37 registering with the opening 24 and through which a portion of the peripheries of the wheels 25 and 26 project. Confined between the wheels 25 and 26 and the strip 17 of paper is an inked ribbon 38 which passes through opening 39 in the plate 35 near its ends and is rolled upon suitably supported spools 40, these spools, in practice, being preferably connected with any suitable mechanism for shifting the ribbon 38 to successively present to the type on the wheels 25 and 26 fresh portions of the ribbon, in order that a clear impression may be made on the strip 17.

Cooperating with the ribbon 38 and the type on the wheels 25 and 26 is a striker 41 which is carried on the end of one arm of a bell-crank lever 42 forming the armature of an electro-magnet 43 in the casing 10 and secured to a wall thereof, the striker 41 being so arranged that when the armature 42 is attracted to the magnet 43 it will be projected through the opening 24 in the plate 22, thus causing the type, which oppose the said striker, to make an impression on the strip 17.

In the operation of the register, the striker 41 is operated at predetermined intervals, in the construction illustrated it being intended that said striker be operated once every minute, and in time with the movement of the wheel 26, whereby the strip 17 of paper, as it is drawn through the machine, will have printed thereon, in longitudinally-spaced relation, numerals indicating each succeeding minute.

Any suitable mechanism may be provided for operating the striker 41. In the construction illustrated, the striker is operated electrically through the medium of an electric circuit by momentarily closing the circuit once every minute, this being effected, in the construction shown, through the medium of a disk 44 which, in practice, would be so connected with the clock-mechanism in the casing 34 as to cause the disk 44 to make a complete rotation once every minute. The periphery of this disk is insulated as represented at 45, with the exception of a small section of metal 46 which serves to close the circuit between two contact-fingers 47 and

48 interposed in circuit with a source of electrical energy and the magnet 43 as hereinafter described.

In the arrangement illustrated, means are provided for indicating on the strip 17 the number of passengers getting on or off the car at either end of the latter, these devices in the illustrated embodiment of my invention being manually controlled and comprising the following mechanism:

Depending from brackets 49 secured to the casing and extending transversely thereof are a plurality of electro-magnets 50, 51, 52 and 53, the armatures of which, represented at 54, are of bell-crank form, 75 being fulcrumed, as indicated at 55, to spaced lugs 56 depending from the brackets 49. The lower arms 57 of the bell-cranks 54 coöperate with the cores 58 of the magnets 50 to 53 inclusive, and the upper arms 59 of these bell-crank levers are provided with fingers 60 which, respectively, oppose openings 61, 62, 63 and 64 in the plate 35. In practice, the fingers 60 would be provided with any means for making a mark, as for example a pencil point, and, in operation, the respective electro-magnets 50 to 53 inclusive would be energized, as hereinafter described, to cause the fingers 60 to be momentarily moved into contact with the sheet 90 95 100 105 110 115 120 125 130 135 140 145 150 155 160 165 170 175 180 185 190 195 200 205 210 sheet 17 indicating the number of passengers alighting from the car.

In the preferred illustrated embodiment of my invention, means are provided for indicating on the sheet 17 the number of times the car stops and the length of the stops during any given period of time, a description of these means being as follows: Located in the casing 10 and supported

10 therein on a bracket 71 secured to the casing-wall is an electro-magnet 72, the armature of which, represented at 73, is of bell-crank form and fulcrumed, as indicated at 74, to spaced arms 75 on the bracket 71.

15 The arm 76 of the bell-crank 73 forms the armature-proper of the magnet 72 and coöperates with the end of the magnetizable core 77. The other arm 78 of the bell-crank 73 is provided with any desirable means for

20 projection through an opening 35^a in the plate 35 to make a mark upon the sheet 17 when the magnet 72 is energized, drawing the armature 76 toward the core 77 and swinging the arm 78 toward the paper 17

25 against the action of a coiled spring 79, secured to the last referred to arm and to a pin 80 on the bracket 71. The illustrated means carried by the arm 78 for making the desired marking on the paper 17 comprises

30 an angular extension 81 carried by the arm 78 and provided with a chamber 82 containing an ink-soaked wicking 83 held in place by a plug 84. The end of the extension 81 is slotted as indicated at 85 and contains

35 a marking disk 86 which is journaled therein on a pin 87 to extend into engagement with the wicking 83, whereby the periphery of the disk 86 is constantly supplied with ink.

40 In the arrangement illustrated, the magnet 72 is caused to be energized at all times, excepting when the car is at a standstill, so that the marking disk 85 will be in contact with the sheet 17 during the entire time the

45 car is in motion, but will be withdrawn from contact therewith when the car is at rest, and to effect this operation of the marking device I provide circuit connections and electrical devices, hereinafter more fully de-

50 scribed, whereby the magnet is energized by the current supplied to the motor of the car, while such current is turned on, and upon shutting off the current to the motor the magnet 72 is energized by the regenerative

55 current produced by the rotation of the motor-armature under the momentum of the car when the current to the motor is shut off.

Desirable circuit connections for the various indicating devices hereinbefore de-
60 scribed when the registering device is used in connection with a trolley-car, are represented in Fig. 6, a description of which is as follows: A trolley wire is represented at 88, this wire, as is common in practice, lead-
65 ing from the power station where it is con-

nected with one side of a dynamo (not shown), the other side thereof being grounded. A trolley is diagrammatically represented at 89, a wire 90 connecting the trolley with the movable arm 91 of a switch 70 which, in practice, would be the usual current-controller provided on trolley cars. The stationary contact of the switch or controller, represented at 92, is connected by a wire 93 with one of the brushes 94 of the car-propelling motor 95, the other brush 96 thereof being grounded as represented at 97, the described circuit connections between the trolley, motor and controller corresponding to the usual circuit connections in trolley cars. A relay 98 has one of its terminals connected with a wire 99 leading from the contact 92, the other terminal 100 of the relay 98 being grounded as represented at 101. The armature of the relay 98 is 85 represented at 102, this armature being adapted to make contact alternately with spaced contact points 103 and 104. The armature 102, which is grounded as represented at 105, is normally held in engagement 90 with the contact 104 through the medium of a coiled spring 106. A relay 107 has its terminals connected with the brush 94 and contact-point 104 through the medium of wires 108 and 109, respectively, the pivoted 95 armature of the relay 107 being represented at 110. This armature, which is grounded as represented at 111, is adapted to be moved into and out of engagement with a contact-point 112, a spring 113 being provided for the purpose of normally holding the armature 110 out of engagement with the contact-point 112 and against a stop 114. The terminals of the electro-magnet 72 are connected, respectively, with wires 115 and 105 116, the wire 115 connecting with the contact-point 112 and with a wire 117 connected with the contact-point 103. The wire 116 connects with one of the terminals of the magnet 53, the other terminal of this 110 magnet connecting with a wire 53^a, which connects with a wire 118 grounded as represented at 119, the push-switch 70 being interposed in the wire 53^a. One of the terminals of each of the magnets 50, 51, and 52 115 is connected with the wire 116 through the medium of wires 120, 121 and 122, respectively, the other terminal of the magnet 52 being connected with the wire 118 through the medium of a wire 123, in which latter 120 the push-switch 69 is interposed. The other terminal of the magnet 51 is connected with a wire 124 in which the switch 68 is interposed, this wire connecting with a wire 125 grounded as represented at 126. A wire 125 127 leads from the other terminal of the magnet 50 and connects with the wire 125, the wire 127 having interposed therein the switch 67. The wire 116 is connected with a wire 128 which is joined to a wire 129 130

connected with one terminal of a battery 130 or any other suitable source of electrical supply, the other terminal of the battery being grounded through a wire 131 as represented at 132. The contact-arm 47 is connected with the wire 129, its co-operating arm 48 being connected with a wire 133 which connects with one of the terminals of the magnet 43, the other terminal of this magnet being connected with a wire 134 grounded as indicated at 135.

It will be understood from the foregoing that the paper is gradually drawn from the reel 15 and wound upon the reel 16 by rotating the latter, the sheet 17 having periodically marked thereon, by the actuation of the striker 41, numerals representing successive periods of time, as for example each succeeding minute, whereby the spaces between each of the time markings described correspond to the movement of the strip 17 during such space of time.

The actuation of the striker 41 to cause it to force the sheet 17 against the type with the ribbon 38 interposed therebetween, is effected through the medium of the rotation of the disk 44 from the clock-mechanism in the case 34, this disk which, in the arrangement illustrated, makes a complete rotation once every minute, serving, when its metal portion 46 contacts the arms 47 and 48, to complete a circuit from the ground at 132 through the wire 131 to the battery 130, thence through wire 129 to contact-arm 47, the section 46 of the disk 44, the contact-arm 48 to wire 133, thence through the magnet 43 and through the wire 134 to the ground at 135.

Assuming that the switches 67 and 68 are located on the front platform and the switches 69 and 70 on the rear platform, the indicating mechanism controlled by the closing of the switches 67 and 69 being provided for indicating the number of passengers boarding the car, and the indicating mechanism controlled by the switches 68 and 70 being provided for indicating the number of passengers alighting from the car, whenever a passenger boards the car or leaves it at either the front or rear platform, the operator, whether he be the motorman or the conductor, as the case may be, closes the appropriate one of the push-switches 67 to 70, which thereby causes the respective one of the magnets 50, 51, 52 or 53, which is controlled by the switch operated, to be energized by the current from the battery 130 which passes through wire 128 to the wire 116, and from said last stated wire to the particular coil controlled by the switch operated, and thence through said coil and to the ground through either the wire 118 or 125, as the case may be, and from the ground through the wire 131 to the battery 130.

The effect of thus operating an electromagnet as stated, is to cause its finger 60 to be projected against the sheet 17, thereby making a mark thereon.

The operation of the running-time indicator of which the disk 86 forms a part is as follows: The movement of the controller-arm 91 by the operator into engagement with the contact 92 to close the circuit in which the motor 95 is located for operating the motor, closes the circuit through the dynamo at the power house, the trolley-wire 88, trolley 89, wire 90, controller-arm 91, contact 92, wire 99, magnet 98, wire 100 to ground at 101 thus completing the circuit and energizing the magnet 98. Thus energizing this magnet causes the arm 102 to be moved into engagement with the contact-point 103, thereby establishing a circuit through the wires 128 and 116, magnet 72, wires 115 and 117, armature 102 to ground at 105, and from ground at 132 through wire 131 and battery 130. So long as current is flowing from the wire 88 through the motor 95, the armature 102 will be held in engagement with the contact 103, with the result of causing the disk 86 carried by the armature 76 to be held against the paper 17. As soon as the controller-switch 91 is operated to open the circuit in which the motor 95 is interposed, the armature 102 assumes the position illustrated in Fig. 6 under the action of the spring 106, wherein it bears against the contact-point 104. The rotation of the armature of the motor 95, after current thereto is shut off, due to the momentum of the car in coasting, causes a regenerative current to be produced which travels from the brush 96 through the armature of the motor 101 to the brush 94, thence through wire 108 to coil 107, and from the coil 107 through the wire 109 to contact-point 104, and armature 102 to the ground at 105, thereby completing the circuit through the grounded brush at 97. Energizing the magnet 107 causes the armature 110 to engage with the contact-point 112, thereby closing the circuit through the coil 72, the current passing from the ground at 111 through armature 110, contact-point 112, wire 115, magnet 72, wires 116, 128 and 129 to battery 130, and from the latter through the wire 131 to ground at 132. The effect of energizing the magnet 72 by the closing of the circuit through the medium of the armature 110 is the same as that described of the closing of the circuit through the armature 102. It will be understood from the foregoing that as the coil 72 is energized by current traversing a circuit which is held closed during the entire time that the current is passing from the wire 88 to the motor 95, and by a separate circuit traversed by the regenerative current produced by the rotation of the armature 125 130

ture of the motor 95, which circuit is created immediately following the break in the circuit controlled by the current passing from the wire 88 to the motor 95, that the marking roller 86 will be held against the paper 17 during the entire time that the car is in motion.

It will be manifest that one observing the sheet 17 after it has passed through the registering mechanism, may readily determine the number of times that the car was stopped during any period of time, the length of time that the car was in motion and consequently the length of time it was standing still, and the number of passengers boarding and alighting from the car during any period of time. With this information before the operating department of an electric railroad, certain of the valuable factors are presented which are necessary in determining the speed at which the car should be run during different periods of the day for operating the cars with the maximum economy, and determining the number of cars required to be run during different periods of the day to accommodate the patrons of the road to the greatest possible practical extent. Furthermore, by proving means for indicating the number of passengers boarding and alighting from the car and the length of stops made by the car, the relative length of time per passenger required for loading and unloading cars of different types may be readily determined.

Instead of providing a separate source of electrical supply, as for example a battery or storage cell, represented at 130, for energizing the magnets 43, 50 to 53 inclusive, and 72, the current may be taken from the trolley 89, as will be readily understood by those skilled in the art.

Various other modifications and alterations may be made in the apparatus illustrated without departing from the spirit of my invention, the particular construction shown being illustrated merely for the purpose of disclosing what I now regard as the preferred embodiment of my invention, but without any intention of limiting my invention further than the prior art may require.

What I claim as new, and desire to secure by Letters Patent, is—

1. The combination of an electrically-driven car, an electric circuit in which the motor of said car and its switch-control is interposed, a shunt-circuit the opening and closing of which is controlled by said switch-control, a regenerative electric-circuit in which the motor is interposed, a car-register comprising, in combination, a record-sheet bearing markings indicating successive periods of time, an electrically-operated device operating to indicate on the sheet the number and length of stops made by the car, and successively-operated electrically-actuated means in said shunt-circuit and electrically-operated means in said regenerative circuit for controlling the action of said electrically-operated device.
2. The combination of an electrically-driven car, an electric circuit in which the motor of said car and its switch-control is interposed, a shunt-circuit the opening and closing of which is controlled by said switch-control, a regenerative electric-circuit in which the motor is interposed, a relay interposed in said shunt-circuit, a relay interposed in said regenerative circuit, a record-sheet bearing markings indicating successive periods of time, an electrical circuit having two branches, the opening and closing of said last referred to circuit through one of said branches being controlled by the armature of the relay in said shunt-circuit and the opening and closing of said last-named circuit through the other of said branches being controlled by the armature of the relay in said regenerative circuit, the armature of the relay in said shunt-circuit operating to control the closing of said regenerative circuit, and an electrically-operated device in said last-named circuit operating to indicate on the sheet the number and length of stops made by the car.
3. The combination of an electrically-driven car, an electric circuit in which the motor of said car and its switch-control is interposed, a shunt-circuit the opening and closing of which is controlled by said switch-control, a regenerative electric-circuit in which the motor is interposed, a relay interposed in said shunt-circuit, a relay interposed in said regenerative circuit, a record-sheet bearing markings indicating successive periods of time, an electrical circuit having two branches, the armature of the relay in said regenerative circuit when attracted to the magnet of said relay operating to close said last-named electrical circuit through one of said branches, means tending to hold said last referred to armature in circuit-breaking position, the other of said branch-circuits comprising a part of said regenerative circuit and provided with spaced contacts, means tending to hold the armature of the relay in said shunt-circuit away from the magnet thereof and in engagement with one of said contacts for closing the regenerative circuit and breaking said last referred to branch circuit, said last referred to armature operating, when attracted by its co-operating magnet, to break the regenerative circuit and close the circuit through said last referred to branch-circuit, and an electrically-operated device in said last-named circuit operating to indicate on the sheet the number and length of stops made by the car.
4. In a car-register, the combination of a record-sheet bearing markings indicating successive periods of time, and means, the

130

6
operation of which is controlled by the opening and closing of the motor-circuit and the generation of the regenerative current by said motor when driving-current is shut off, 5 for indicating on the sheet the number of stops made by the car.

5. The combination of an electrically-driven car, an electric circuit in which the motor of said car and its switch-control is 10 interposed, a shunt-circuit the opening and closing of which is controlled by said switch-control, a regenerative electric-circuit in which the motor is interposed, a car-register comprising, in combination, a record-sheet 15 bearing markings indicating successive periods of time, an electrically-operated device operating to indicate on the sheet the number of stops made by the car, and successively-operated electrically-actuated means 20 in said shunt-circuit and electrically-operated means in said regenerative circuit for controlling the action of said electrically-operated device.

6. The combination of an electrically-driven car, an electric circuit in which the motor of said car and its switch-control is interposed, a shunt-circuit the opening and closing of which is controlled by said switch-control, a regenerative electric-circuit in 25 which the motor is interposed, a relay interposed in said shunt-circuit, a relay interposed in said regenerative circuit, a record-sheet bearing markings indicating successive periods of time, an electrical circuit having 30 two branches, the opening and closing of said last referred to circuit through one of said branches being controlled by the armature of the relay in said shunt-circuit and the opening and closing of said last-named 35 circuit through the other of said branches being controlled by the armature of the relay in said regenerative circuit, the armature of the relay in said shunt-circuit operating to control the closing of said regenerative 40 circuit, and an electrically-operated device in said last-named circuit operating to indicate on the sheet the number of stops made by the car.

7. The combination of an electrically-driven car, an electric circuit in which the motor of said car and its switch-control is 45 interposed, a shunt-circuit the opening and

closing of which is controlled by said switch-control, a regenerative electric-circuit in which the motor is interposed, a relay interposed in said shunt-circuit, a relay interposed in said regenerative circuit, a record-sheet bearing markings indicating successive periods of time, an electrical circuit having 55 two branches, the armature of the relay in said regenerative circuit when attracted to the magnet of said relay operating to close said last-named electrical circuit through one of said branches, means tending to hold said last referred to armature in circuit-breaking position, the other of said branch-circuits comprising a part of said regenerative circuit and provided with spaced contacts, means tending to hold the armature of the relay in said shunt-circuit away from 60 the magnet thereof and in engagement with one of said contacts for closing the regenerative circuit and breaking said last referred to branch circuit, said last referred to armature operating, when attracted by its co-operating magnet, to break the regenerative circuit and close the circuit through said last referred to branch-circuit, and an electrically-operated device in said last named circuit operating to indicate on the sheet the 65 number of stops made by the car.

8. In a car-register, the combination of a traveling record -sheet having markings thereon indicating successive periods of time, a plurality of electrically-operated devices with operating means therefor adapted to be located at the opposite ends of the car on which the register is to be used, for indicating on the sheet the number of persons boarding and alighting from the car, 70 electrically-actuated means, the operation of which is controlled by the closing of the circuit in which the motor of the car is interposed, and the regenerative current created by the motor in its movement after driving 75 current thereto is cut off for indicating on said sheet the number of stops made by the car, and means for moving said sheet, for the purpose set forth.

JAMES D. ELSOM.
